UNITED STATES PATENT OFFICE.

BARTLETT ARKELL, OF NEW YORK, N. Y., ASSIGNOR TO ARKELL SAFETY BAG COMPANY, OF NEW YORK, N. Y., A CORPORATION OF NEW YORK.

MACHINE FOR MAKING STRETCHABLE CRINKLED PAPER.

1,405,384.

Specification of Letters Patent. Patented Feb. 7, 1922.

Application filed June 12, 1919. Serial No. 303,659.

To all whom it may concern:

Be it known that I, BARTLETT ARKELL, a citizen of the United States, residing in the borough of Manhattan, city, county, and State of New York, have invented certain new and useful Improvements in Machines for Making Stretchable Crinkled Paper, of which the following is a full, clear, and exact description.

This invention relates to a machine for making stretchable crinkled paper of the type that is used for packing and wrapping purposes.

In the manufacture of crinkled paper it is desirable that the paper be moistened before it is placed on the receiving roll and acted upon by the doctor to form the crinkles in the paper. After the paper has received these crinkles, it must again be dried and in such a manner that the crinkles are not destroyed during the drying. The drying process requires a considerable amount of heat and renders the rooms more or less uncomfortable.

It is an object of this invention to condition the paper while in the web for being placed upon the receiving roll so that it may be crinkled by the doctor with a minimum amount of moisture content. By so reducing the moisture content less heating will be required to subsequently dry the crinkled paper.

Another object of my invention is to subject the paper while in the web to successive wetting and squeezing operations, so that the moisture will be compelled to permeate all parts of the web.

Other objects of the invention will appear as the description proceeds.

In the drawings, wherein I have shown three of the many possible embodiments of my invention,

Figure 1 is an elevation of the machine showing the essential parts of the completed machine;

Fig. 2 is a section taken on plane 2—2 of Fig. 1;

Fig. 3 is an elevational view of a machine modified from what is shown in Fig. 1 and showing but one of the wetting and squeezing devices; and

Fig. 4 is a view similar to Fig. 3 showing a further modified form.

According to the form of the invention, as shown in Figs. 1 and 2, a main frame 5

carries at one end a suitable supporting bracket 6 for the roll 7 of finished paper from which it is fed while in the web as at 8 to the various parts of the machine.

Also mounted on this frame is a tank or receptacle 9 adapted to contain a bath 10. In this bath a plurality of immersing rolls 11 are carried, these rolls being submerged in the bath 10. On the top of the frame and over the tank 9, a plurality of squeezing devices are located. These squeezing devices 12 comprise a fixed rubber-faced roll 13 and an adjustable rubber-faced roll 14 mounted in suitable boxes 15 and provided with compressible springs 16 and hand wheels 17 whereby the pressure between the rolls may be adjusted.

The first roll at the left, as shown in Fig. 1, is preferably placed substantially so that its axis is located directly above the axes of the immersing rolls 11 and half way between them. In the form shown, three sets of immersing rolls 11 and three sets of squeezing devices 12 are shown. I do not intend to limit myself to three such devices, for I may use more or less as conditions require, and I may not use all of the devices on a machine at all times.

At the opposite end of the frame 5, a power shaft 18 is mounted, which carries a suitable driving pulley 19 at one end, and another driving pulley 20 on the opposite end. A belt passes over the pulley 20 and about a suitable pulley arranged at one end of one of the squeezing rolls. As shown, it connects with a pulley 21 carried on the back side of the right hand squeezing device. Another pulley 22 is carried on the front side of the first squeezing device. The other two squeezing devices carry the same sized pulleys and are driven by the belts 23 and 24 as shown.

Also driven from the shaft 18 is a receiving roll 25 and associated with this receiving roll is the doctor blade 26 which crinkles the paper as it is driven against it. Near the receiving roll 25 an adjustable pressure roll 27 is also carried by the main frame.

The web 8 of paper, as it comes from the roll 7, is directed over a roller 28 and under the left immersing roll 11. It then goes upwardly and about the lower roll 13 of the left side of squeezing devices, where any excess moisture will be expelled and where the moisture will be forced through the

thickness of the paper. From the first squeezing device the paper is fed under the next immersing roll 11. The paper is passed from this immersing roll through the next 5 squeezing and immersing rolls which act in succession on it.

The main driving belt 29, acting on pulley 19, draws the paper through the machine and as it passes it about the receiving roll 10 25 and against the doctor blade 26, the paper is taken off the receiving roll in a crinkled condition.

According to the modification of the invention shown in Fig. 3, the web 8 of paper 15 is passed between two pipes 30 which carry water under pressure, the pipes having suitable holes 31 therein so that the water is forced out in the form of a light spray against the paper from both sides. The 20 wetted sheet is then passed through squeezing devices 12' similar to the squeezing devices 12 before described. The drawing shows but one set of wetting and squeezing devices, but it is understood that a plurality of each of these is contemplated, and that the paper will pass through them in 25 succession.

According to the modification shown in Fig. 4, the web 8 is wetted by being passed 30 between rollers 32 and 33. The roll 33 has a felt covering 34, and is supplied from the interior 35 through perforations 35' with water to wet the felt. The wetted felt will then dampen the paper as it is passed 35 through. Similar squeezing devices 12'' are used as before, and a plurality of wetting and squeezing devices is contemplated.

For some qualities and weights of paper 40 more immersing and squeezing operations will be necessary than for other types of paper, and in the case of paper requiring fewer wettings and squeezings than the machine is capable of applying, the web may be directed so that it will not pass about 45 all the immersion rolls 11, that is, it might go directly from roll 28 to the left squeezing device 12, or from one squeezing device direct to the other.

The water or other liquid with which the 50 paper is wet should be hot and preferably near the boiling point as high temperature of the wetting liquid promotes permeation of the paper. If desired, the pipes 30 in Fig. 3 may supply steam to wet the paper 55 instead of water or other liquid.

While I have shown the invention and its modifications in what I believe to be the best and most efficient form, it will be understood that various changes may be made 60 without departing from the scope of the invention.

I claim:

1. In a machine for making stretchable crinkled paper, the combination with a

smooth faced receiving roll adapted to have 65 paper deposited thereon and a doctor associated with the roll against which the paper is carried for crinkling, of wetting means and squeezing devices through which the paper passes before it reaches the receiving 70 roll.

2. In a machine for making stretchable crinkled paper, the combination with a smooth faced receiving roll adapted to have 75 paper deposited thereon and a doctor associated with the roll against which the paper is carried for crinkling, of wetting means and a plurality of squeezing devices, means to pass the paper from the wetting means to the squeezing devices successively, and 80 means to press the paper against the receiving roll before it reaches the doctor.

3. In a machine for making stretchable crinkled paper, the combination with a smooth faced receiving roll adapted to have 85 paper deposited thereon and a doctor associated with the roll against which the paper is carried for crinkling, of a plurality of wetting and continuously driven squeezing 90 devices operating in succession and arranged to deliver dampened paper to the receiving roll.

4. In a machine for making stretchable crinkled paper, the combination with a smooth faced receiving roll adapted to have 95 paper deposited thereon and a doctor associated with the roll against which the paper is carried for crinkling, of wetting means and squeezing devices through which the paper passes before it reaches the receiving 100 roll, said squeezing devices comprising rubber faced rolls.

5. In a machine for making stretchable crinkled paper, the combination with a smooth faced receiving roll adapted to have 105 paper deposited thereon and a doctor associated with the roll against which the paper is carried for crinkling, of wetting means and squeezing devices through which the paper passes before it reaches the receiving 110 roll, said squeezing devices comprising adjustable rubber faced rolls.

6. In a machine for making stretchable crinkled paper, the combination with a smooth faced receiving roll adapted to have 115 paper deposited thereon and a doctor associated with the roll against which the paper is carried for crinkling, of wetting means and squeezing devices through which the paper passes before it reaches the receiving 120 roll, and means to press the paper against the receiving roll before it reaches the doctor.

7. In a machine for making stretchable crinkled paper, the combination with a 125 smooth faced receiving roll adapted to have paper deposited thereon and a doctor associated with the roll against which the paper

- is carried for crinkling, of means including a bath and a plurality of squeezing rolls to subject the paper to a plurality of wetting and squeezing operations in succession, and 5 means to deliver the paper from the last squeezing roll on to the receiving roll.
8. In a machine for making stretchable crinkled paper, the combination with a smooth faced receiving roll adapted to have 10 paper deposited thereon and a doctor associated with the roll against which the paper is carried for crinkling, of means including a bath and a plurality of squeezing rolls to subject the paper to a plurality of wetting and squeezing operations in succession, and 15 means to deliver the paper from the last squeezing roll on to the receiving roll, said squeezing rolls being individually adjustable.
- 16 9. The step in the method of crinkling paper which comprises subjecting the paper to a plurality of wetting and squeezing operations in succession.
10. The step in the method of crinkling 25 paper which comprises drawing the paper

through wetting and squeezing devices in succession by driving each squeezing device.

11. The step in the method of crinkling paper in the web which comprises subjecting the web to a plurality of wetting and 30 squeezing operations in succession.

12. The step in the method of crinkling paper in the web which comprises drawing the web through wetting and squeezing devices in succession by driving each squeezing 35 device.

13. The step in the method of crinkling paper in the web which comprises continuously subjecting the web to a plurality of wetting and squeezing operations in suc- 40 cession.

14. The step in the method of crinkling paper in the web which comprises continuously drawing the web through wetting and squeezing devices in succession by driving 45 each squeezing device continuously.

This specification signed this 6th day of June, 1919.

BARTLETT ARKELL.
